DESIGN FOR A TOY FERRY BOAT

George L. Crawford, Jamestown, R. I.

Application October 12, 1945, Serial No. 122,806

Term of patent 14 years

(Cl. D34—15)

To all whom it may concern:

Be it known that I, George L. Crawford, a citizen of the United States of America, residing at Jamestown, county of Newport, State of Rhode Island, have invented a new, original, and ornamental Design for a Toy Ferry Boat, of which the following is a specification, reference being had to the accompanying drawing, forming a part thereof.

Fig. 1 is a plan view showing my new design for a toy ferry boat;

Fig. 2 is a side elevation thereof; and

Fig. 3 is an end view thereof.

I claim:

The ornamental design for a toy ferry boat, substantially as shown.

GEORGE L. CRAWFORD.
